UNITED STATES PATENT OFFICE.

CLYDE M. CLEFTON, OF AUSTIN, MINNESOTA, ASSIGNOR TO FLORENCE K. CLEFTON, OF AUSTIN, MINNESOTA.

OIL BURNER.

Application filed January 21, 1924 Serial No. 687,544.

The object of my invention is to provide an oil burner adapted particularly for heating purposes in the fire-pot of a boiler, furnace, or other type of heater.

5 A further object is to provide an oil burner in which provision is made for the proper combustion and a blue burning flame.

A further object is to provide a burner in which there would be practically no carbon 10 deposits resulting in clogging and necessary cleaning of the burner and one which will be very accurate and reliable in its action and require practically no attention when once it has been properly installed except to supply 15 the necessary fuel.

A further object is to provide an air check damper or air valve that is controlled by the operation of the burner.

A further and particular object is to provide improved means governed by the temperature of the rooms to be heated for regulating the feed of liquid fuel to the burner.

The invention consists generally in various constructions and combinations all as 25 hereinafter described and particularly pointed out in the claims.

In the accompanying drawings forming part of this specification,

30 Figure 1 is a view of a conventional form of heater showing the application of my invention thereto;

Figure 2 is a sectional view through a portion of the heater illustrating the manner of mounting the burner therein;

35 Figure 3 is a sectional view on the line 3—3 of Figure 1 showing the position of the valves in the retort for controlling the flow of the fuel;

Figure 4 is a detail view showing the position 40 of the check damper in the flue;

Figure 5 is a detail sectional view showing the feed of the liquid fuel to the retort.

In the drawing, 2 represents a heater having the usual flue 3 for the products of combustion. 4 represents the grate below the fire pot, and upon the grate I place a ring 5. Encircling this ring 5 is a second ring 6 having set screws 7 by means of which it may be clamped on the ring 5 in different positions 45 to raise or lower the ring 6 as desired. Suitable fire brick 8 enclose the rings 5 and 6 leaving a space in the center of the grate through which air may flow upwardly through the rings. The upper part of the ring 6 is pro-

vided with a wall 9 that is closed except for a 55 central opening 10 therein. A disk 11 is fitted over said opening and has a stud 12 that is tapped into a hub 13 formed in said opening. When the disk is raised, currents of air may flow between it and the walls of the opening, the volume of air being governed by the width of the space or passage. When the disk is in its lower position, the opening will be nearly closed against the passage of air; hence, by adjusting this disk up and down I 60 am able to regulate to a nicety the volume of air delivered to the burner. The wall 9 has sockets 14 therein and hollow standards 15 are mounted in said sockets and project upwardly therefrom and have ports 16 near 65 their upper ends through which auxiliary currents of air are delivered to the space above the disk 11.

I have found the means for delivering the auxiliary currents of air at intervals around the mixing chamber is an important feature of the invention as it enables me to provide the proper proportion of air and obtain the desired blue-burning flame. The number of ports delivering air horizontally to the mixing chamber may of course be increased or diminished as desired and the area of these ports may be varied to suit different conditions of use.

The upper ends of the standards are preferably open, and elbows 17 have studs 18 fitting within said standards, the other ends of the elbows being mounted in the wall of a retort 19 that is centrally supported above the disk 11 and a distance therefrom equal substantially to the height of the standards. This distance may be increased or diminished as desired. I have found, however, that a space of 3 to 4 inches is sufficient to produce the best results.

The upper wall of the retort has an opening 20 and a flange 21 encircling said opening and a cap 22 by means of which access is permitted to the interior of the retort. A liquid fuel feed pipe 23 is mounted at one end in the flange 21 and has a passage 24 therethrough leading to the retort and through which the liquid fuel is discharged into the retort. A supply pipe 25 communicates with the liquid fuel feed pipe and is provided with a regulating valve 26 and a suitable strainer 27 all of which is of any ordinary or preferred construction. The lower walls of the retort

have nipples 28 and 29 tapped therein and provided with ports 30 and 31 adapted to be closed by valves 32 and 33, one of said ports being comparatively small and the other comparatively large and the valves are correspondingly formed to fit the ports. The stems of the valves extend upwardly through the retort and are pivotally connected to a crank disk 34 that is centrally mounted on the inner 10 end of an operating rod 35 that is preferably concentric with the liquid fuel feed pipe 23; the rod being journaled in the walls of the flange 21 and the disk being secured to the rod for rotary adjustment by suitable means 15 such as a set screw 36. The connections of the valves with this crank disk are on opposite sides of the axis and consequently when the disk is rotated by the movement of the rod, one valve will be opened and the other closed, 20 this movement being performed alternately with the rocking of the valve-controlling rod. A suitable stuffing-box 37 is provided at the point where the rod 35 passes out of the feed pipe and an operating lever 38 is mounted on 25 said rod and has its ends attached to flexible connecting means 39 and 40 which extend to the motor of the thermostatic control, the operation of the motor rocking the lever 38 and rotating the rod 35 on its axis to open one of 30 the retort valves and close the other one. Flexible means such as a chain 41 also connects the cable 39 with the draft door 42 of the furnace so that when the larger valve is 35 opened the draft door will be simultaneously opened to increase the flow of air to the burner.

The flue 3 has a damper 43 hinged at 44 and provided with a weight 45 which normally tends to hold the damper in a closed position, allowing it to open when there is a sufficient suction in the flue to overcome the gravity of the weight. This movement to an open position occurs when there is a strong draft in the chimney and flue and the damper 42 45 is open and more air is passing to the burner than is needed or desired. At such time, the intake of air by the opening of the damper 43 will cut down the flow through and around the burner maintaining the desired volume 50 under different conditions. By increasing the weight 45 the damper will not open as readily and a greater volume of air will be delivered to the burner before the damper in the flue will be affected. In this way, I am 55 able to regulate to a nicety the supply of air to the burner.

The wall 9 in the upper part of the fire pot ring has a basin 46 therein that is adapted to receive any overflow of the liquid fuel from 60 the disk 11 and the feed valves above. An overflow pipe 47 communicates with this basin or pan and leads to a point outside the heater and delivers the overflow to a receptacle 48 that is suspended on the lever of a 65 control valve 49. When sufficient fuel has

been delivered to this receptacle it will descend and close the valve, shutting off the supply of fuel to the burner. This device is intended as a safeguard against flooding the heater and the basement with the liquid fuel 70 in case the burner flame should accidentally become extinguished, or should the thermostatic device fail to control the fed and more fuel be delivered to the burner than could be consumed in its ordinary operation. 75

In the operation of the device, the fire pot rings are placed on the grate of the heater and enclosed with suitable fire brick or clay and the disk 11 is adjusted to deliver the desired amount of air, and fuel is then admitted to the retort the priming charge being placed in the pan below the disk 11 and ignited. The walls of the retort will soon become heated and the fuel delivered thereto will be vaporized and discharged through the valves into the space beneath the retort where the vapor will be mixed with air passing up around the disk 11 and with air discharged through the ports 16. A combustible mixture will thereby be obtained and a blue flame provided that will furnish an intense heat within the furnace with practically complete combustion. Whenever desired, the disk 11 may be raised or lowered to increase or decrease the air space beneath it and regulate thereby the volume of air delivered to the mixing chamber. I have found that by furnishing a supply of air below the mixing chamber and delivering air at intervals around the chamber that I am able to effect a very complete combustion 90 of the fuel with the desirable blue flame. 95

As heretofore described, the valves 32 and 33 operate alternately. In mild weather the valve 32 will be opened, delivering a comparatively small supply of fuel to the mixing chamber. In cold weather, when the thermostat will open the drafts of the furnace, the position of the valve will be reversed the large valve 33 opening and the small valve closing, admitting thereby a larger supply of fuel to the mixing chamber and greatly increasing the heating capacity of the burner. With this apparatus, no pilot light is necessary. A small flame is burning continuously 100 as long as the burner is in use, the valve 32 105 and its port having the function of the usual pilot light. 110

The wires or cables 39 and 40 lead to an operating motor, the movement of which is controlled by a thermostat in the room or 115 space where the temperature is to be regulated; therefore, the lever 38 will be actuated by the operation of the motor and the valves changed when the motor is started by the closing of a thermostatic circuit. The 120 thermostatic system of temperature control is well known and I have not therefore thought it necessary to illustrate it in detail herein, it being common practice to connect 125 dampers of heaters with a motor that is 130

electrically controlled by the action of a thermostat located at a distant point.

I claim as my invention:

1. In a liquid fuel burner, a retort having discharge ports of different size in its bottom wall and corresponding valves for said ports, a rotating rod and a crank disk thereon whereto said valves are connected, the rotation of said rod opening and closing said valves alternately to increase or decrease the flow of fuel to the burner, a base having a priming pan and standards upon said base supporting said retort.

2. In a liquid fuel burner, a base adapted to be placed on the grate of the heater and having an air passage therein, an air deflector above said passage, a retort supported above said air passage to form a mixing chamber thereunder, means for delivering a liquid fuel to said retort, and a plurality of different sized ports and regulating valves for delivering the vaporized fuel into said mixing chamber, the air flowing around said deflector and mingling with the vaporized fuel.

3. In a liquid fuel burner, a base adapted to be seated on the grate of the heater and having an air passage therein, hollow standards mounted on said base and having discharge ports in their walls, a retort supported by said standards, the space beneath said retort and enclosed by said standards forming a mixing chamber, the lower wall of said retort having a discharge port therein, and means for delivering a liquid fuel to said retort, the vapor discharged from said retort

mixing with the air flowing upwardly through said base and discharged laterally from said hollow standards.

4. In a liquid fuel burner, a base having an air passage therein, standards mounted on said base and having air passages and ports leading therefrom, a retort supported by said standards and having means for delivering a liquid fuel thereto and provided in its lower walls with ports of varying size and valves for said ports, one of said valves being comparatively small and forming a pilot light port, said ports delivering the vapor into the space beneath said retort to mix with the air therein, and means for alternately opening and closing said valves and ports.

5. A liquid fuel burner comprising a base portion having a priming pan and an air intake opening and means above said opening for deflecting the air currents outwardly from said opening, upright hollow standards mounted on said base, a retort supported by said standards and having a fuel intake and a port and valve therefor for delivering the vaporized fuel into the mixing chamber between said retort and said air-deflecting means to mingle with the currents of air from said opening, and air ducts in said hollow standards communicating with an air supply whereby additional air will be delivered to said mixing chamber.

In witness whereof, I have hereunto set my hand this 10th day of December, 1923.

CLYDE M. CLEFTON.
